HOLDER AND POSITIONER FOR HEEL PARTS

Emerson C. Gill, Melrose, Mass., assignor to
United Shoe Machinery Corporation, Flemington, N. J., a corporation of New Jersey

Application December 12, 1942, Serial No. 468,774

5 Claims. (Cl. 1—32)

1

This invention relates to machines by which fastenings, such as fiber pegs, are driven to effect the connection of work-pieces. Machines of this character may be employed for the attachment to shoes of heel-parts, as bases and lifts of rubber or the like.

In heel-attaching machines, a base and a rubber lift are commonly presented to the inserting die in superposed relation to receive contact of the heel-seat of a shoe to which they are to be secured. My invention has as an object the provision of holders into which the heel-parts may be readily introduced by the operator and which will locate said parts accurately with respect to the fastening-receiving openings of the die and to each other. This I accomplish by the employment of two pairs of pivoted arms arranged one above the other, one pair holding a heel-base and the other a heel-lift, together with means for forcing the arms of each pair yieldably toward each other. Each arm of a pair is preferably provided with two projections for engagement with the heel-part to be held, arranged to contact with the corresponding part and locate it from front to rear of the machine and turn it about an axis heightwise of the heel-parts until said parts are arranged in a predetermined angular relation to each other and to the inserting design in accordance with which are arranged elements of fastening-inserting mechanism. This positioning is attained without the necessity for consideration on the part of the operator. To provide for the correct presentation to the fastening-inserting mechanism of the heel-parts of different sizes and different nailing designs, the arms are preferably pivoted upon carriers which may be varied in position independently in a direction from front to rear of the heel-parts. To prevent injury to the arms by movement resulting from compression of the work, their projections are shown as mounted to yield heightwise of the heel-parts, this being especially applicable to the base-holder.

The guard for the die-projections and the means which insures the matching and registration of elements of the fastening-inserting mechanism are made the subjects of divisional applications, Serial No. 544,495 filed July 12, 1944, and Serial No. 544,494 filed July 12, 1944, respectively, the latter application having become Patent No. 2,376,910, May 29, 1945.

In the accompanying drawings:

Fig. 1 shows, in side elevation with elements in section, portions of a heel-attaching machine with

which the present invention is more directly concerned;

Fig. 2 is a front elevation of the lower portion of Fig. 1;

Fig. 3, an enlarged transverse sectional detail through the lift-engaging elements, taken prior to the clamping of the work;

Fig. 4, a top plan view corresponding to Fig. 1, but with portions omitted;

Fig. 5, a top plan view of the die-block and more closely associated elements, with parts broken away to show the lift-holder;

Fig. 6, a top plan view of the base-holder, removed from the machine;

Fig. 7, a detail in front elevation of the closure for the fastening-inserting mechanism, and its controlling elements;

Fig. 8, a front elevation of the starting lever of the machine and its connections;

Fig. 9, a side elevation of the elements shown in Fig. 8;

Fig. 10, a view similar to Fig. 3, but with the work under pressure;

Fig. 11, a view of the lift-holder, corresponding to Fig. 6; and

Fig. 12, an enlarged detail in broken front elevation of one of the forward pairs of lift- and base-engaging members of the holder mechanism.

The general organization of a heel-attaching machine to which the present invention is applicable may be that disclosed in Letters Patent of the United States No. 2,293,624, Parkhurst, August 18, 1942, and in certain respects in No. 2,207,742, La Chapelle, July 16, 1940, these machines being designed for the attachment of heel-bases and top-lifts to shoes. In apparatus of this character, there is mounted upon a frame 10 a die-block 12, in which are vertical passages 14 to receive the fastenings to be inserted. These passages may include a multiple of all the designs which are to be employed. The die-block is shown as separably mounted in place by screws 16 threaded vertically into the frame. The portion of the die-block with which the work contacts is provided by a plate 18, carried in ways 20 at the underside of the die and latched in place by a spring-plunger 22, movable through said die and entering an opening at the front of the plate. The passages through the plate correspond to those of a particular nailing design in the die terminate in depending quills 24. The quills enter the surface of a rubber or other elastic lift to be attached, and compress the material over the area therein through which the attaching fastenings are to be driven. These fastenings

55

pass through this lift and a heel-base, carried at the underside of the die-quill-plate by holder mechanism M, and into the heel-seat of a shoe which is pressed against the base by a vertically reciprocable jack (not illustrated) and upon which it is supported. The fastenings are preferably cut from strings of fiber F (Fig. 1), delivered through tubes 26 terminating in a foot-plate 28, and severed by a loader-block 30 having a compound movement of translation and oscillation. Actuated by mechanism 32 (Fig. 4), the loader-block delivers the cut fastenings to the die-block-passages 14. The insertion of the fastenings in the work is effected by a gang of drivers 34, which may first act as awls, as in the previously mentioned La Chapelle patent. These drivers are fixed in a plate 36 carried by a top-girt 38 upon side rods 40, 40 reciprocating vertically in the frame 10. The plate 36 is separably mounted in opposite ways 42 upon the top-girt, it being latched by a spring-plunger 44 movable in said top-girt and received in a depression in the edge of the plate. The gang of drivers operates in the corresponding group of multiple die-passages 14, it being changed together with the quill-plate 18 as the inserting design varies. The side rods 40 are actuated from power mechanism through a clutch (not shown).

Considering now the features peculiar to this invention, the mechanism M includes a heel-base-holder m and a top-lift-holder m' (Figs. 5, 6, 11 and 12). The respective holders have carrier members 50, 50', each of which is of L-shape and has an arm 52 or 52' extending from front to rear of the machine, from the rear extremity of which projects a transverse arm 54 or 54'. The arms 52 and 52' of the two holders lie at opposite sides of the die-block 12, while the arms 54 and 54' are superposed, the arm 54' of the holder m' being uppermost. They are adjustable fore and aft by virtue of their support upon the heads of screws 56 or 56', threaded vertically into the underside of the die-block and passing through slots 58 or 58' extending longitudinally of the carrier-arms 52. One of the rear screws 56'' at the opposite ends of the transverse arms 54 and 54' may be common to the two carriers, through openings 58'' in which they pass. To vary the position of the holders, the forward extremity of each of the arms 52 and 52' has a depression 60 or 60' in which lies a collar 62 or 62' upon a screw 64 or 64', threaded horizontally into the front of the die-block and rotatable by a head 66 or 66'. With the screws 56 and 56' loosened, either of the screws 64 or 64' may be turned by its head situated conveniently for the operator at the front of the machine, and the holders m and m' brought to the correct relation to each other and to the passages in the die-block for the particular inserting design in use. In this adjusted position, the carriers may again be locked by tightening the screws 56 and 56'. Each of the carrier-arms 54 and 54' is depressed between its extremes to receive a pair of locating and grasping arms for heel-parts, those for the base-holder m being designated as 70, 70 and those for the lift-holders m' as 72, 72. The arms of the pairs 70 and 72 are pivoted separately at 74 and 74', respectively, upon the arms 54 and 54' of their carriers and cross each other from the pivots to their forward heel-part-engaging portions. Each of the pairs of arms 70 and 72 are given support against downward deflection by a screw 68 or 68', threaded upwardly into the arm 52 or 52' of the corresponding carrier 50 or 50' and

passing through an arcuate slot 69 or 69' in the lower arm of the pair. This lower arm rests upon the head of the screw, and, in turn, supports the upper arm which moves in contact with it at the point of intersection of the arms. The arms of each pair are geared at 76 or 76' to oscillate together, and the approach of their forward ends under the influence of a tension-spring 78 or 78' connecting them is adjustably limited by a stop-screw 80 or 80' threaded horizontally through one and engaging the other. For contact with a periphery of a lift inserted between the arms of the holder m' (Fig. 11), there is located upon their inner edges in front of the intersection of said arms opposite projections 82, 82, while at their forward extremities are rotatable about vertical axes rolls 84, 84 having reduced peripheral portions (Fig. 3). Upon the arms of the base-holder m (Fig. 6) are similarly situated rear contact members 88, 88 and forward contact members 90, 90. These are shown as levers fulcrumed at 92 beneath the arms and each urged normally down at its inner end by an expansion-spring 94 interposed between it and the arm upon the inner side of the fulcrum. The contact of the outer end of the lever with the arm determines its normal angular position. As indicated at 96 in dash-lines in Fig. 6, contact-rolls may be placed upon the inner ends of the levers 90, if this be desirable.

In applying heel-parts to the holders m and m', the operator presses a lift T between the rolls 84, the arms 72 of the holder m' yielding against their spring 78' to admit the lift and the rotation of the rolls facilitating the inward movement. This continues until the rear of the lift at the opposite sides of the longitudinal axis strikes the arm-projections 82. These furnish a back-stop which determines the position of the lift along this longitudinal axis. As the operator frees the lift, the pressure of the rolls against the opposite sides between the breast and the center will turn said lift about a vertical axis, if it is not already symmetrically located, until the longitudinal axis is centralized with respect to the passages 14 in the die-block 12 and its quills 24. In this rotation of lift, it remains in engagement with the projections 82, so its position from front to rear of the die-block is determined. A heel-base H is similarly inserted between the arms of the holder m against the levers 88, the unfinished periphery projecting beneath the reduced peripheries of the rolls 84 and is turned by the contact of the inner ends of the levers 90 or the rolls 96 upon them, its correct location both longitudinally and angularly being attained in the same manner as the lift T.

Were it necessary to insert the lifts into the holder m' in contact with the ends of the spaced quills 24, there would tend to be interference with the movement. To prevent this, the lower portions of the quills are shrouded by guard-plate 100. This plate is movable in a recess at the underside of the quill-plate 18 (Fig. 3), it being held against downward displacement by the heads of screws 102, which extend through openings in the quill-plate and are threaded vertically into the guard-plate. In the guard-plate is an opening 104 for the reception of each quill, the lower end of which lies normally above the lower surface of the plate (Fig. 3). In its lowered position, the guard-plate is yieldably maintained by expansion-springs 106 having their opposite extremities seated in recesses in the quill-plate and guard-plate. The

underface of the guard-plate presents a surface free from interfering projections when the top-lifts are slid into place in the holder m' . Yet, when clamping pressure goes upon the work (Fig. 10), as a result of the elevation of the shoe-supporting jack in preparation for the insertion of the fastenings by the drivers 34, the guard-plate yields freely, so the quills will enter the substance of a rubber lift.

Since the drivers 34 and the associated quill-plate 18 of the die 12 with its guard-plate 100 must be changed whenever the inserting design is altered, it is important that there be means for ensuring the matching of the driver-assembly and the quill-plate, and that they are in their proper positions before operation of the machine. This is to avoid damage by contact of the drivers with the die and possible consequent injury to the operator. I accomplish the desired result in the following manner. The space above the die is closed, when the machine is in operation, by a door 110 hinged at 112 at the left of the frame 10 (Fig. 7). This door interposes a shield between the inserting mechanism and the operator, and has a transparent panel 113 through which the delivery of fastenings by the loader-block 30 to the die may be seen. The inner side of the door is provided with a testing member for the driver-plate 36 and for the quill-plate 18. This member is shown as in the form of a vertical bar 114 rising from a carrier-block 115 (Figs. 1, 4 and 5), which is adjustably attached to the door by a screw 118 passing through either of two horizontal slots 120, 120 in said door and threaded into the block (Fig. 7). The inner edge of the bar is reduced at 122, and, receiving this reduced portion, when the door is closed, is a depression 124 in the forward edge of the driver-plate and a depression 126 in the quill-plate. These depressions are in vertical registration for each matching pair of plates and are differently arranged in each pair transversely of the machine for all the inserting designs. When the operator must change the position of the driven fastenings because of the differing character of the work, he adjusts the matching bar in one or the other of the slots 120, until it will enter the vertically aligned depressions 124, 126. Consequently, when the door can be closed, it follows that the driver-plate and quill-plate supplied will co-operate correctly, if each is fully in place and latched by the respective plungers 44 and 22. In the reciprocation of the driver-assembly, the depression 124 in the plate 36 travels freely along the bar-portion 122.

That the proper positioning of the fastening-inserting elements may be made certain, the condition of the retaining plungers 44 and 22 controls the full closure of the door 110. At the lower portion of the inner side of this door is a projection 128. When the door is closed, the under face of the projection lies just above the head of the plunger 22. Therefore, until said plunger has entered the depression in the newly applied quill-plate, the shutting of the door cannot be completed, and the operator will thus know that the quill-plate is not in place. With the plunger in the quill-plate-depression and the door-projection 128 above it, not only is the door closed, but the locking of the plate is maintained. Similarly, the closure of the door is governed by a vertically elongated projection or rib 130 at the inner right portion of said door. If the locking plunger 44 for the driver-plate is not seated in the plate-depression, the rib will strike

5

the head of the plunger and hold the door against closing. With the driver-plate fully in place and the door closed, the head of the plunger in the reciprocation of the drivers moves along and in close proximity to the adjacent vertical surface of the rib, so the driver-plate cannot be unlocked accidentally.

The door 110 having provided for the matching and correct positioning of the fastening-inserting elements as above described, it is further caused to prevent the power-operation of the machine and consequent reciprocation of the drivers 34, until this has been accomplished. Such a result is attained by locking the starting mechanism of the machine against actuation by the operator, until the door is closed. The clutch, through which power is applied to reciprocate the side rods 40, is tripped by movement of a rod 132 guided in a bracket 134 attached to the frame 10 (Figs. 8 and 9), and movable downwardly and rearwardly against the force of an expansion-spring 136 interposed between the rod and the bracket. This movement of the rod is effected by a hand-lever 138 fulcrumed upon the bracket and having threaded through it a screw 140, which contacts with the upper end of the rod. A rearwardly extending arm 142 of the lever is pivoted to a bar 144, guided at 146 upon the frame (Fig. 7) for upward movement when the lever is depressed. The upper end of the bar lies just below the plane of the underface of a locking slide 148. This slide is guided for horizontal movement upon the frame in front of the die-block 12, and when the machine is in condition for operation the right end of the slide terminates short of the upper end of the bar 144. At its opposite extremity, the slide has formed upon it rack-teeth 150 with which meshes a pinion 152 surrounding the door-hinge 112 and turning with the door. When said door is closed, the pinion holds the locking slide at its extreme position to the left, in which the other end leaves the bar free to be raised. The operator can at this time lower the hand-lever 138 and trip the clutch to start the machine in operation. If the door is out of its fully closed position, the gearing between the door and slide at once carries the end of said slide over the bar. This locks the hand-lever against actuation so, if the closure of the door is prevented by mismatched fastening-inserting elements or by their improper location, starting of the machine is impossible. That the door when closed shall so remain during the operation of the machine, maintaining the fastening-inserting elements in their correct relation, it is shown as latched by a spring-plunger 154, movable vertically in its lower free portion and engaging a retaining member 156 projecting from the frame 10 (Figs. 4 and 7). An inclined surface 150 at the forward extremity of the member serves, by contact of the plunger with it, to lift this as the door approaches closure, said plunger entering a latching depression 160 in the retaining member when the door is fully closed.

Assume that the machine of this invention is to be employed for the attachment to a shoe of a heel-base H and an elastic lift T, by fastenings cut from strings F of fiber and driven through pricked openings in said lift and base, and that it is necessary to change the inserting design. The door 110, which has been closed during the preceding operation, is freed from the latch 154 and opened. The operator then releases the driver-assembly by withdrawing the plunger 44,

and removes it, and similarly frees the quill-plate 18 from the plunger 22 and takes it from the machine. He, thereupon, selects another pair of these fastening-inserting elements arranged in accordance with the chosen design, and inserts them in their respective ways 42 and 20. With the inserting elements properly matched and fully positioned, their respective depressions 124 and 126 will register or be in vertical alinement, and the door 110 may be closed, its bar-portion 122 having been adjusted to the correct transverse position to enter these depressions. Further, if the new pair of inserting elements has been fully seated in their ways, their latches 44 and 22 will have engaged the respective depressions in the driver-plate 36 and the quill-plate 18, and will be out of the path of the door-projections 130 and 128. Therefore, the closure of the door is not interfered with in this respect, and when fully shut and secured by the latch 154, the gearing 152, 150 between the door and the locking slide 148 will have drawn said slide toward the left to free the starting lever 138 of the machine, ready for actuation. Taking one of the lifts, the operator pushes it back into the holder m' , it moving smoothly over the plane surface at the underside of the plate 100 (Fig. 3) which guards the die-quills 24, and between the rolls 84. When the lift contacts with the arm-projections 82, its rearward progress is arrested, and, as it is released by the operator, the forcing of the rolls against the periphery near the breast will turn it upon the projections 84 in such a direction as to centralize it angularly, as well as to maintain it located longitudinally with reference to the shoe to which it is to be attached. The base H may now be forced between the arms 70 of the holder m and positioned in a like manner. For the particular work in hand, the carriers 50 and 50' of the two holders will have been adjusted through the screws 64 and 64' to properly register the lift and base with each other and with the quills 24. A shoe is jacked and its heel-seat pressed against the cup of the base H to clamp the work for the inserting operation. As pressure is applied, the plate 100 yields against the springs 106 and the quills are seated in the substance of the lift to compress the elastic material (Fig. 10). The operator depresses the lever 138, freed by the full closure of the door 110, to trip the driving clutch. A power-cycle of the machine is thereupon performed, the loader-block 30 severing a group of discrete fastenings from the strings F and delivering them above the die-passages 14 to be inserted in the work by the drivers 34,

which have previously been actuated to prick openings to receive these fastenings. The shoe with its attached base and lift may now be freed for removal from the machine.

Having described my invention, what I claim as new and desire to secure by Letters Patent of the United States is:

1. In a heel-attaching machine having fastening-inserting mechanism provided with fastening-receiving passages and co-operating fastening-drivers arranged in accordance with an inserting design, the combination of a pair of pivoted base-engaging arms, a pair of pivoted lift-engaging arms, and means for yieldably forcing the arms, of each pair toward each other, the pairs of arms being located one above the other and each pair being provided with projections arranged to contact with a base or lift to locate it in a direction from front to rear of the inserting design of the fastening-inserting mechanism and by their lateral pressure to turn it about an axis heightwise of the heel-parts into a predetermined angular relation to the said design and to the associated heel-part.
2. In a holder for heel-parts, a pair of pivoted arms each provided with a projection for engagement with the periphery at the rear of a heel-part at each side of its longitudinal axis and with a projection for engagement with such periphery adjacent to the breast, such projections being mounted upon the arms to yield heightwise of the heel-part, and means for yieldably forcing the arms toward each other.
3. In a heel-attaching machine, a fastening-inserting die, two carriers movable upon the die bodily in a direction from front to rear thereof, means arranged to vary the position of each carrier, and a pair of heel-part-engaging arms pivoted upon each carrier for engagement with opposite sides of a heel-part.
4. The combination with a fastening-inserting die, of two L-shaped carriers having arms situated at opposite sides of the die and arms extending from the opposite arms and being superposed, means for connecting the carrier-arms adjustably to the die, and heel-part-engaging arms pivoted upon the superposed carrier-arms.

5. The combination with a fastening-inserting die, of two L-shaped carriers having arms situated at opposite sides of the die and arms extending from the opposite arms and being superposed, there being slots in the arms, clamping screws extending through the slots into the die, and heel-part-engaging arms pivoted upon the superposed carrier-arms.

EMERSON C. GILL.
